Patented Nov. 28, 1972

225,281

BOAT UPPER SHELL

Edward W. Peterson, Bannockburn, Ill., assignor to
Silverline, Inc., Moorhead, Minn.

Filed Sept. 17, 1970, Ser. No. 25,035

Term of patent 7 years

Int. Cl. D12—06

U.S. Cl. D71—1

Fig. 1.

Fig. 3.

*Fig. 4.**Fig. 5.*FIG. 1 is a rear perspective view of a boat upper shell showing my new design;

FIG. 2 is a top plan view thereof;

FIG. 3 is a side elevation view thereof;

FIG. 4 is a front elevation view thereof; and

FIG. 5 is a rear elevation view thereof.

The boat hull shown in broken lines in FIGS. 1, 3, 4, and 5 is included for illustrative purposes only, and the opposite side of the boat upper shell is a mirror image of FIG. 3.

I claim:

The ornamental design for a boat upper shell, as shown and described.
